UNITED STATES PATENT OFFICE

DENNIS C. GALVIN, OF DES MOINES, IOWA

DISK SHARPENER

Application filed June 4, 1929. Serial No. 368,272.

My invention relates to that type of disk sharpeners in which there is provided a pair of parallel rolls, one being yieldingly held toward the other for the purpose of admitting the edge portion of a disk between them, and rolling it out to a sharp edge on a true circle.

The object of my invention is to provide means of simple, durable and inexpensive construction for holding a disk to be sharpened in proper position relative to the rolls.

More specifically it is my object to provide a disk adjusting and supporting device in which the disk may be forcibly inserted between the rolls and forcibly tilted to any desired angle relative to the rolls and there firmly held in place during the operation of the rolls, and to provide such means so arranged that the various adjustments may be made during the operation of the rolls with the edge of the disk between the rolls.

My invention consists in the construction, arrangement and combination of the various parts of the device, whereby the objects contemplated are attained, as hereinafter more fully set forth, pointed out in my claim, and illustrated in the accompanying drawings, in which:

Figure 1 shows a front elevation of a disk sharpener embodying my invention, the position of the disk being indicated by dotted lines.

Figure 2 shows a side elevation of a part of a disk sharpener with my improved disk holder and adjusting mechanism applied thereto, parts thereof and of the disk being broken away.

Figure 3 shows an enlarged, vertical, sectional view taken on the line 3—3 of Figure 1.

Figure 4 shows an enlarged, detail, transverse, sectional view taken on the line 4—4 of Figure 3; and

Figure 5 shows a like view taken on the line 5—5 of Figure 3.

Referring to the accompanying drawings, I have used the reference numeral 10 to indicate generally the frame of a disk sharpener. Mounted in this frame are the rolls 11 having rounded forward ends which project in front of the machine. These rolls are

customarily yieldingly held one toward the other by a spring not shown.

My improved disk supporting and adjusting attachment comprises a main frame 12 having slidingly mounted therein a disk supporting plate upon which there is a socket 14 designed to receive and rotatively support a short shaft 15, at the upper end of which are the arms 16. A disk 17 is placed in position on the arms 16 and there detachably held by means of a bolt 18 extended through the disk and seated in the upper end of the shaft 15, as shown in Figure 2.

Mounted in suitable bearings in the frame 12 is a shaft 19 having a squared outer end at 20 to receive a crank for turning the shaft. This shaft is screw threaded throughout the greater portion of its length and is extended through a screw threaded opening in the frame 13, as shown in Figure 3.

By this arrangement it is obvious that when the shaft 19 is rotated, the disk supporting plate 13 will be moved longitudinally of the frame 12, and considerable power can be applied to the disk supporting plate on account of this screw action. Furthermore, the disk supporting plate will be held by the screw firmly fixed during any part of its movement, thereby enabling the operator to effect this longitudinal movement forcibly and to hold it in any position in which it is placed, even during the operation of the rolls upon a disk carried by the disk supporting plate.

The inner ends of the frame 12 are pivotally connected to brackets 21 which are provided with screw threaded openings, and each of which has a screw threaded rod 22 extended through it. These rods 22 are rotatively mounted in the main frame 10 on opposite sides of the rolls 11, and at their upper ends they are provided with angular extensions 23 to which a wrench or the like may be applied for rotating the rods, and effecting a vertical adjustment of the inner end of the main frame 12.

In this connection I have found in use that at times it is desirable to tilt one edge of the frame 12 higher or lower than the other end, for the purpose of forcing an irregularly

shaped disk between the rolls or temporarily holding it in such position until the irregularly shaped portion of the disk has been rolled out to a substantially true circle.

5 For supporting the outer end of the main frame 12, I have provided an extensible frame comprising an upper member 24 and a lower member 25 slidably connected with each other, as shown in Figure 5. The upper end of the frame member 24 is pivotally connected to the outer end of the frame member 12 by the hinge members 26. In this connection I preferably make this hinge joint loosely fitted so that the outer end of the 10 frame 12 may be tilted slightly.

In the lower extensible frame member 25 there is a lug 27, and in the frame member 24 there is a corresponding lug 28. A screw threaded rod 29 extends through the lug 27 and has a bearing in the lug 28, and the opening in this lug 27 is screw threaded to receive the rod 29. The upper end of the rod is provided with a squared end at 30 to receive a wrench or crank, or the like, for turning the 20 rod. The lower end of the frame member 25 is pivotally connected at 31 with the main frame 10, and this pivotal connection is so arranged as to permit slight tilting movements.

30 In practical use, the disk to be sharpened is first placed upon the arms 16 and there held by the bolt 18. Then the disk supporting plate is tilted to such an angle that the edge of the disk will be approximately parallel 35 with the meeting edges of the rolls. Then the shaft 19 is rotated to force the disk to position within the rolls, preferably to a distance about three-fourths of an inch from the cutting edge of the rolls. Then the rolls are 40 operated in the ordinary manner and during this operation, the disk is rotated. The disk is permitted to turn when in this position for sufficient revolutions to permit the rolls to roll out any irregularities in that portion of 45 the disk which is engaged by the rolls, and during this time the operator need not be in attendance, because the disk is firmly held against movement in all directions except rotation about its own axis.

50 Then the operator again adjusts the device either by tilting the inner end of the frame 12 upwardly or downwardly with the screw 22, or by tilting the outer end of the frame 12 upwardly or downwardly by the 55 screw 29, or tilting the inner end of the frame 12 laterally by the adjustment of one or the other of the screws 22. Any and all of these adjustments may obviously be made while the rolls are in motion, and while the operator can 60 readily see what action the rolls are producing upon the disk, and not only upon a certain portion of the disk, but on the entire circumference of the disk, and this is very important because disks to be sharpened are usually distorted, and when the rolls are operating upon 65

distorted portions of the disk, it is practically impossible for the operator to hold the disk by hand in position during the entire rotation of the disk, and yet it is essential that it be so held in order that the complete disk may be 70 rolled out true.

This operation of making the adjustment by means of screws continues until the edge of the disk is rolled out to the final edge, and this results in a rerolling or reshaping of the 75 disk in a uniform manner throughout its circumference and in sharpening the edge of the disk.

I claim as my invention:

The combination with a disk sharpener having sharpening rolls, of a frame, a disk supporting plate slidably mounted in the frame, a disk support rotatively mounted in the disk supporting plate, means for forcibly moving the disk supporting plate longitudinally of the frame and fixing it in any position of its adjustment, two brackets pivotally connected to the inner corners of said frame, two adjusting screws mounted in upright positions upon the disk sharpener and on opposite sides of the sharpening rolls, and having threaded connections with said brackets and provided with means whereby they may be independently rotated, to thereby raise or lower the inner end of said frame, or to tilt 80 said inner end of the frame laterally, and an auxiliary frame having its lower end pivoted to a stationary support and its upper end connected to the outer end of the main frame by means of a hinged joint loosely fitted so that the outer end of the main frame may be 85 tilted slightly in a lateral direction upon the adjustment of said screws in said clips.
